UNITED STATES PATENT OFFICE.

SYLVESTER K. MATHEWS, OF ALBANY, NEW YORK.

PENCIL SHARPENER.

Application filed October 17, 1922. Serial No. 595,197.

To all whom it may concern:

Be it known that I, SYLVESTER K. MATHEWS, a citizen of the United States, and a resident of Albany, in the county of Albany and State of New York, have invented a new and Improved Pencil Sharpener, of which the following is a full, clear, and exact description.

This invention relates to sharpening devices and has particular reference to a pencil sharpener.

An object of the invention is to provide a pencil sharpener wherein the pencil is sharpened by rotary and oscillatory movements of the pencil with respect to the cutting blades.

Another object is to facilitate the sharpening of the pencil by providing a container or receptacle into which the shavings from the pencil are directed as the same are cut from the pencil.

The above and other objects will appear more clearly from the following detail description, when taken in connection with the accompanying drawing, which illustrates a preferred embodiment of the inventive idea.

In the drawing—

Figure 1 is a top plan view of the pencil sharpener constructed in accordance with the invention;

Figure 2 is a vertical sectional view on the line 2—2 of Figure 1;

Figure 3 is a bottom plan view of the device;

Figure 4 is a section on the line 4—4 of Figure 5 showing a pencil in position to be sharpened and illustrating the sharpener detached from the receptacle; and

Figure 5 is a side elevation of the sharpener detached from the receptacle so that the same may be carried about the person.

The device consists of a body portion 6 of any desired configuration, having a bottom section 7 hingedly connected to the body, as at 8 and provided with a spring latch 9 engageable with the bottom edge of the body to maintain the bottom section in closed position, said latch being adapted to be disengaged from the body and the bottom section 7 swung downwardly about its pivot to empty the receptacle 6 of shavings which are collected therein when the pencils are sharpened, as will appear in the course

of the description. The top of the contain-

er or receptacle 6 is provided with a vertically arranged bearing 10 in which a post or standard 11 is adapted to be mounted and secured in position by means of the wing nut 12 which may be reached by moving the bottom section 7 to an open position. The upper end of the post or standard 11 which extends beyond the bearing 10 has secured thereto a sleeve 13, preferably arranged in an inclined position with respect to the horizontal and adapted to receive therein the handle 14 of the sharpener proper. The inner end of the handle 14 is provided with a pair of spaced lugs 15 through which a pivot pin 16 extends transversely with respect to the handle and to which adjacent ends of the cutting blades 17 are secured. At a point intermediate the ends of the cutting blades 17 the same are bent so that the free ends of said blades converge, as best illustrated in Figure 1, and the lower cutting edges 18 of the blades are rounded and tapered toward the free ends thereof.

Also carried by the pivot pin 16 and positioned exteriorly of the lugs 15 and cutting blades 17 is an oscillatory member, generally indicated by the numeral 19 and which includes oppositely disposed guards or flanges 20, which converge downwardly, as indicated in Figures 1 and 4, and which have their lower edges 21 curved to substantially the contour of the cutting blades 17. The oscillatory member 19 also includes a pencil holder 22 in the form of a sleeve 90 which is split longitudinally to provide resilient pencil engaging portions whereby pencils of various diameters may be inserted into the holder and held in proper position therein. The sleeve 22 extends transversely of the pivot pin 16 so that when the pencil 23 is inserted into the sleeve or holder the same will extend longitudinally of the cutting blades 17 and the oscillator member 19 and the sleeve is so disposed that the pencil will be arranged in a plane between said cutting blades. The ends of the guards 20 remote from the pivot 16 are connected by a transverse stop 24 against which the end of the pencil to be sharpened engages so as to properly position said end with respect to the cutting blades.

When the pencil is in position the outer end thereof is grasped and the member 19

is swung about the pivot 16 to engage the end of the pencil to be sharpened with the cutting edges 18 of the blades 17 and due to their converging relation, it will be obvious that said blades will cut into the end of the pencil each time the same is brought into contact with said cutting edges. After each cutting operation the member 19 is moved about its pivot in an opposite direction and the pencil 23 is given a slight rotation in the holder 22 so that the next cutting operation will sever a different portion of the end of the pencil. By repeating this operation it will be obvious that the pencil may be given an even and well defined point, after which the same may be withdrawn from the holder or sleeve 22.

In order that the shavings from the pencil may be accumulated in the receptacle 6 and thus facilitate the sharpening of the pencil, the receptacle or container 6 is provided at a point opposite the latch 9 with an opening 25 for receiving the lower end of a chute 26, which extends outwardly and upwardly from the receptacle. The side members 27 of the chute 26 are disposed on either side of the cutting blade 17 and the guards 20 of the oscillatory member 19 and are widened at their upper ends to substantially enclose said parts whereby the shavings from the pencil will be directed by the side members into the bottom of the chute 26 and from thence in the receptacle 6. The upper ends of the side members 27 are provided with outwardly flared flanges 28 which also aid in directing the shavings into the chute 26.

It will be obvious from the foregoing description that should it be desired to use the sharpener including the cutting blade 17 and the oscillatory member 19 without employing the receptacle 6 and chute 26, said sharpener may be detached from the receptacle by removing the wing nut 12 and then extracting the post 11 from the bearing 10, after which the handle 14 may be withdrawn from the sleeve 13. The operation of sharpening the pencil in this instance is practically the same as that previously described except that instead of having the handle 14 rigidly connected to the receptacle 6 the same may be grasped with one hand and the pencil with the other hand, whereupon the cutting blades and oscillatory member may be moved about the pivot 16 relative to each other to secure the cutting action upon the end of the pencil positioned between the cutting blades and guards 20.

60 What is claimed is:

1. In a pencil sharpener, cutting blades converging toward adjacent ends thereof, an oscillatory member having pivotal connection with said blades at the other ends thereof, and including guards extending exterior-

only of said blades, and a pencil holder carried by said member and positioned in a plane between said blades.

2. In a pencil sharpener, cutting blades converging toward adjacent ends thereof, an oscillatory member having pivotal connection with said blades at the other ends thereof and including guards extending exteriorly of said blades, a pencil holder carried by said member and positioned in a plane between said blades, and a stop carried by said member remote from its pivotal connection for properly positioning a pencil in said holder with respect to said blades.

3. In a pencil sharpener, a handle, cutting blades extending longitudinally from one end of said handle, a member having a portion pivotally connected to said end of the handle and between said blades and including a pencil holder arranged on one side of said pivot and positioned with respect to said blades whereby a pencil in the holder will have a portion disposed between said blades, and guards also forming a part of said member arranged on the opposite side of said pivot and cooperating with said blades.

4. In a pencil sharpener, a handle, cutting blades extending longitudinally from one end of said handle, a member having a portion pivotally connected to said end of the handle and between said blades and including a pencil holder arranged on one side of said pivot and positioned with respect to said blades whereby a pencil in the holder will have a portion disposed between said blades, guards also forming a part of said member arranged on the opposite side of said pivot and cooperating with said blades, and a stop connecting said guards at the ends thereof remote from said pencil holder and engageable by a pencil in said holder to properly position the pencil with respect to said cutting blades.

5. In a pencil sharpener, a receptacle having an opening, a standard supported thereby, a handle carried by said standard and having cutting blades at one end thereof and arranged above said receptacle, a pencil holder pivotally connected to said handle and arranged in a plane between said blades, and a chute having its lower end extending into the opening in said receptacle and its upper end extending to a point above and on opposite sides of said cutting blades whereby said blades are positioned between the side walls of said chute.

6. In a pencil sharpener, a receptacle having an opening, a standard supported thereby, a handle carried by said standard and having cutting blades at one end thereof and arranged above said receptacle, a pencil holder pivotally connected to said handle and arranged in a plane between said blades, and a chute having its lower end extending

into the opening in said receptacle and its upper end extending to a point above and on opposite sides of said cutting blades whereby said blades are positioned between the 5 side walls of said chute, the upper ends of said side walls terminating in outwardly flared flanges.

7. In a pencil sharpener, a receptacle having an opening therein, a chute extending

upwardly from said receptacle and having 10 its lower end disposed in said opening, said chute including an outer wall and side walls, a handle supported by said receptacle and having cutting blades extending into said chute between the side walls thereof, and a 15 pencil holder pivoted to said handle and disposed in a plane between said cutting blades.
